CONTROL MECHANISM FOR PUMPS

Henry W. Landenberger, Philadelphia, Pa., assignee to American Engineering Company, Philadelphia, Pa., a corporation of Pennsylvania

Application March 26, 1935, Serial No. 13,096

9 Claims. (Cl. 60—52)

This invention relates to control mechanisms, and more particularly to mechanisms for controlling the operation of pumps.

One object of the present invention is to provide an improved control mechanism for pumps, which functions to maintain the pump on stroke throughout a predetermined pressure range in the system, to actuate the stroke adjusting means toward neutral position when the pressure in the system exceeds a predetermined value, and under predetermined conditions to maintain the pump on leakage stroke at a comparatively low pressure.

A more specific object is to provide a control mechanism for pumps which comprises a pair of rams, one of said rams being constantly connected to the pressure in the system while the other is connected thereto only under predetermined conditions at which time both rams function to maintain the pump on leakage stroke.

Other and further objects will become apparent as the description of the invention progresses.

Of the drawings, Fig. 1 is a diagrammatic view of the fluid control system showing certain of the elements thereof in section.

Fig. 2 is a side elevational view partly in section, of the high pressure pump and the control mechanism associated therewith.

Fig. 3 is a side elevational view of a portion of the control mechanism associated with a high pressure pump.

Fig. 4 is a diagrammatic view partly in section of the hydraulic press and a portion of the hydraulic circuit including the control valves, showing the flow of fluid in the system when one of the valves is moved to its upper position of adjustment, and,

Fig. 5 is a similar view showing the flow of fluid in the system when both valves are moved to their upper position of adjustment.

Referring to the drawings, the numeral 1 designates generally the fluid control system, which in the present instance comprises a pump unit 2, manually actuated valves A and B, automatic valve C, and an hydraulic press 3.

The pump unit 2 comprises a high pressure pump H and a low pressure pump L, suitably mounted upon a supply or makeup tank T. Pumps H and L are of the general type shown and described in the United States Patent No. 1,077,979, and in the present instance are driven by an electric motor M. Fluid is drawn into pump H from makeup tank T through a pipe 4, and is discharged from said pump through a pipe 5. Pipe 5 is connected to a central port 6 of valve A. In a like manner fluid is drawn into pump L

from tank T through a pipe 7 and is discharged therefrom through a pipe 8. Pipe 8 is connected to pipe 5 and by means of a check valve 9 a reverse flow of fluid therein to pump L is prevented.

Valve A is provided with a substantially cylindrical chamber 10 in which a pair of spaced interconnected valve members 11 and 12 operate. These valve members may be shifted by a lever 13 pivoted at one end to a link 14 which in turn is pivoted to a bracket 15 secured to and extending outwardly from valve A. Valve A in addition to port 6 has provided in the casing thereof ports 16 and 17, communicating with chamber 10, and a passage 19 which connects the opposite ends of chamber 10 communicates with a fourth port 18.

Press 3 comprises an upper cylinder 20 having a piston 21 operating therein, a lower cylinder 22 having a piston 23 operating therein, and an intermediate stationary forming mold 24. Piston 21 is provided with a reduced portion 25 forming with the inner walls of cylinder 20 an annular chamber 26, and to the end of which is secured a forming platen 27. Piston 23 has secured to the upper end thereof a holding platen 28. The purpose of platens 27 and 28 will appear fully hereinafter.

Valve B is also provided with a cylindrical chamber 29 having spaced interconnected valve members 30 and 31 operating therein. Valve members 30 and 31 may be shifted by a lever and link mechanism 32 similar to that shown in connection with valve A. Valve B has provided in the casing thereof ports 33, 34 and 35 which communicate with chamber 29.

Valve C comprises an upper chamber 36, an intermediate chamber 37, and a lower chamber 38. The upper chamber 36 is connected to pipe 8 by a branch pipe 39, and has provided therein a valve 40 which normally prevents the passage of fluid to intermediate chamber 37 through the connecting passage 41. A coil spring 42 extends between valve 40 and a spring seat 43 provided at the upper end of said chamber and a set screw 44 is provided to adjust the tension of said spring. A pipe 45 connects intermediate chamber 37 with makeup tank T. Lower chamber 38 has provided therein a comparatively large piston 46, the reduced portion 47 of which extends upwardly through and is guided in a cylindrical opening between chambers 37 and 38. The upper end of reduced portion 47 engages the lower end of the stem 48 of valve 40. A pipe 49 connects pipe 5 with the lower end of chamber 38. It therefore is evident that when the pressure in the system exceeds the tension of spring 42 piston 46 will

unseat valve 48 and thus permit the discharge of pump L to bypass to makeup tank T through chamber 38, passage 41, chamber 37 and pipe 45.

Returning to valves A and B, it is seen that a pipe 50 connects the upper end of cylinder 20 with port 16 of valve A. A pipe 51 connects port 17 of valve A with a pipe 52; one end of the latter is connected to the lower end of cylinder 20, while the other end thereof is connected to port 18 of valve B. A pipe 53 connects the lower end of cylinder 22 with port 33 of valve B, and a pipe 54 connects port 34 with makeup tank T. A check valve 55 is provided in pipe 52 to normally prevent a reverse flow of fluid from cylinder 22. A branch pipe 56 having a check valve 57 provided therein connects pipes 50 and 52 as shown in Fig. 1, and a pipe 58 connects port 18 of valve A with makeup tank T. A comparatively small pipe 59 connects discharge pipe 5 of pump H with a fluid motor 60 mounted at one end of pump H, while a second pipe 61 connects pipe 52 with a second fluid motor 62 mounted at the opposite end of said pump. Fluid motor 60, therefore, is always connected to the pressure in the system, while fluid motor 62, it will be observed, is connected to the pressure in the system only when fluid enters the lower end of cylinder 20.

Motor 60 in the present instance comprises a bracket 63 secured to the pump casing in any suitable manner, such as by bolts 64, and has provided therein a cylinder 65 in which operates a piston 66. Cylinder 65 communicates with a port 66' to which one end of pipe 59 is connected. A gland 67 secured to bracket 63 prevents leakage past the piston 66. The left hand end of piston 66 (Fig. 2) abuts against a crossbar 68 through the opposite ends of which extend a pair of rods 69 and 70, the inner ends of said rods being secured to the sliding block 71 of pump H, as shown in Figs. 1 and 2. A pair of nuts 72 and 73 provided at the outer end of rods 69 and 70 respectively, secure crossbar 68 thereto and permit adjustment of said crossbar to and from the piston 66. Secured to rods 69 and 70 intermediate the ends thereof are a pair of blocks 74 and 75 respectively, to which are pivotally connected the lower ends of a pair of levers 76 and 77. These levers are pivoted intermediate their ends on a rod 78 mounted in bracket 63, as shown more particularly in Figs. 2 and 3, and are pivotally attached at the upper ends thereof as shown at 79, to pintles provided on the outer ends of a crosshead 80. Crosshead 80 is slidably mounted on a rod 81 secured to the upper end of bracket 63 in any suitable manner, such as by a nut 82. Rod 81 has provided thereon a coil spring 83 which extends between a spring seat 84 mounted adjacent crosshead 80 intermediate the ends thereof, and an adjustable spring seat 85. Spring seat 85 is mounted near the right hand end of rod 81, and may be adjusted by means of nuts 86. By this arrangement, it is seen, that when spring 83 is compressed it will urge crosshead 80 to the left (Fig. 2) causing levers 76 and 77 to swing in a counterclockwise direction, which through their connection with rods 69 and 70 place the pump H on stroke in a well known manner. Pump H will remain on stroke until the pressure in the system exceeds the tension of spring 83, when piston 66 will swing the levers 76 and 77 in a clockwise direction, thereby placing the pump on leakage stroke.

Motor 62 comprises a cylinder 87 having a piston 88 operating therein. Cylinder 87 is se-

cured to the right hand end (Fig. 2) of pump H by means of bolts 89, as shown in Figs. 1 and 2. The free end of piston 88 engages a crossbar 90 having secured to the opposite ends thereof a pair of rods 91 and 92, the inner ends of which are connected to sliding block 71 of pump H. A gland 93 secured to the left hand end of cylinder 87 prevents leakage of fluid past said piston. Cylinder 87 is provided with a port 94 to which pipe 61 is connected. From this arrangement it is seen that when pressure is applied to motor 62, sliding block 71 will tend to move to the left.

From the above description, the operation of my improved control mechanism is believed to be obvious. However, in order to correlate the various elements, a brief résumé of the operation thereof will now be given.

The operator first adjusts the tension of spring 42 of valve C the desired amount; for example, if it is desired that fluid discharged from the low pressure pump should bypass when the pressure in the system exceeds 150 pounds per square inch, spring 42 is adjusted to retain valve 48 upon its seat until this pressure is exceeded. In a like manner, the tension of spring 83 is adjusted the desired amount, say, for example, to resist a pressure in the system of 1000 pounds per square inch at the end of the compressing action thereof. Valves A and B are then adjusted to the position shown in full lines in Fig. 1. The apparatus is now conditioned for operation.

Fluid from pumps H and L will now discharge into the annular chamber 26 of cylinder 20 through pipes 5 and 8, valve A, and pipes 51 and 52. Fluid will also flow to the lower end of cylinder 22 through pipe 52, check valve 55, valve B, and pipe 53. Pistons 21 and 23 will now move upwardly until platen 28 engages the lower end of forming mold 24, and the upper end of piston 21 engages the abutment at the upper end of cylinder 20. When this occurs, continued operation of the pumps will cause the pressure to build up in the system and when this pressure exceeds 150 pounds per square inch, piston 46 in valve C will move upwardly, unseating valve 48, thereby permitting fluid from the low pressure pump L to bypass to makeup tank T through chamber 38, passage 41, intermediate chamber 37, and pipe 45. The high pressure pump H, however, will continue to operate until the pressure in the system communicated to motors 60 and 62 is sufficient to overcome the tension of spring 83. When this occurs sliding block 71 of pump H will be moved to the left (Fig. 2), thereby placing said pump on leakage stroke. Inasmuch as both motors 60 and 62 are now operating against the action of spring 83, the pump H is held on leakage stroke at a materially reduced pressure.

The press 3 is now conditioned for operation and the work may be placed in the forming mold 24. When the press has been so loaded the operator then adjusts valve members 11 and 12 of valve A by manipulation of lever 13 to the position shown in Fig. 4. Fluid from the annular chamber 26 of cylinder 20 will now enter the lower end of chamber 18 of valve A through pipe 52, and thence flow through passage 19 and pipe 58 to the storage or makeup tank T. The pressure in the system is now reduced and spring 83 urges sliding block 71 to the right (Fig. 2), placing the pump on stroke. When valve A is adjusted in this manner, it will be noted that motor 62 is disconnected from the pressure in the system and therefore is ineffective.

Fluid under pressure from pump H now enters the upper end of cylinder 20 through valve A and pipe 50. As a result of the reduction in pressure in the system caused by connecting chamber 10 to exhaust, as described above spring 42 of valve C will urge valve member 40 upon its seat, thereby closing the bypass, and fluid from the low pressure pump L will also enter the upper end of cylinder 20 through pipes 8 and 5, valve 10 A, and pipe 50. Thus, the combined discharges of pumps H and L are operative upon piston 21, which moves downwardly at a comparatively high rate of speed. When platen 27 engages the work the pressure in the system again builds up 15 and when this pressure exceeds the tension of spring 42, which, as previously stated, has been set at 150 pounds per square inch, piston 46 will again unseat valve 40, thereby causing the fluid discharging from pump L to bypass to makeup 20 tank T. The high pressure pump, however, continues to operate to compress the work in the mold until the developed pressure exceeds 1000 pounds per square inch, the pressure to which spring 83 is adjusted. When the pressure in 25 the system exceeds this value piston 66 of motor 60 urges sliding block 71 toward neutral or leakage stroke position and the pressure may thus be maintained upon the work for any desired period of time. Inasmuch as the cross sectional 30 area of piston 23 is greater than that of piston 21, and due to the connection of cylinder 22 with pipe 50 through pipe 56, valve B, and pipe 53, the piston 23 will be held in its uppermost position against the pressure exerted upon the work by piston 21. After the materials in the mold have 35 been under compression the desired period of time, the operator actuates valve members 30 and 31 of valve B by manipulation of lever 32 to the position shown in Fig. 5. When valve B is so 40 adjusted the fluid in cylinder 22 will bypass to storage tank T through pipe 53, chamber 29 of valve B, and pipe 54. As a result the pressure in the system is again reduced and spring 83 again places pump H on stroke, causing fluid 45 under pressure to be discharged through pipe 5 and thence to the upper end of cylinder 20, causing piston 21 to continue its downward movement. When the pressure decreases to 150 pounds per square inch low pressure pump L 50 will also become effective to assist in this downward movement of platen 27. Platen 27 continues to move downwardly in this manner, causing the work formed in the mold to be ejected therefrom, which then may be removed by the 55 operator.

This downward movement of piston 21 may continue until it engages the lower end of cylinder 20, when the pressure in the system again builds up. When this pressure exceeds 1000 pounds per square inch, pump H will again be placed on neutral or leakage stroke by the fluid motor 60 as hereinbefore described. However, when the work is ejected from the mold, the operator usually moves levers 13 and 32 of valves A and B respectively to the full line position shown in Fig. 1 to condition the press for another operation. Pistons 21 and 23 will then be moved to their uppermost positions as previously described, by the combined discharges of pumps H and L. 60 When piston 21 reaches the upper end of cylinder 20, the pressure in the system again builds up. At this time it will be remembered that both of the fluid motors 60 and 62 operate in unison, to adjust the pump to, and maintain 65 the same on leakage stroke position. The pres-

sure required to maintain the pump on leakage stroke, therefore, is materially reduced.

It therefore is seen that a highly efficient control mechanism has been provided. By reducing the pressure required to maintain the pump on 5 leakage stroke, the load imposed on the motor M is also reduced, with the result that undue strains on the apparatus are not only minimized, but the cost of operation thereof is greatly reduced. It also is believed to be clear that pump 10 H and the control mechanism associated therewith form a unitary construction which is adaptable for general use.

The invention therefore, it is to be understood, 15 is not to be limited to the embodiment herein shown, since it may be embodied in other forms, all coming within the scope of the claims which follow.

What is claimed is:

1. In a fluid system, the combination with a 20 variable stroke pump, of a fluid motor operated by said pump, means for controlling the operation of said motor including a valve, means for placing said pump on stroke, means for returning said pump to leakage stroke position, said last mentioned means comprising a pair of servo motors, one of said servo motors being constantly connected to the discharge pressure in the system and adapted to return the pump to leakage stroke 25 position when the pressure in the system exceeds a predetermined value, means for actuating said valve to control the operation of said fluid motor and to connect the second of said servo motors to said discharge pressure whereby said second fluid motor operates in the same direction as said 30 first mentioned servo motor to return the pump to and maintain the same on leakage stroke position 35 at a comparatively low pressure:

2. In a fluid control system, the combination 40 with a variable stroke pump, of resilient means for placing said pump on stroke, means for actuating said pump to and retaining the same on leakage stroke position, said last mentioned means comprising a pair of fluid motors, one of 45 said motors being constantly connected to the discharge pressure in the system, and a valve for connecting the other of said motors to said discharge pressure, whereby the combined action of said motors maintains said pump on leakage stroke position at a relatively low pressure. 50

3. In a fluid control system, the combination 55 with a variable stroke pump, of adjustable resilient means for placing said pump on stroke, means for actuating said pump to and retaining the same on leakage stroke position, said last mentioned means comprising a pair of fluid motors, one of said motors being constantly connected to the discharge pressure in the system 60 and adaptable to return said pump to leakage stroke position when the pressure in the system exceeds the tension of said resilient means, a valve for connecting the other of said motors to said discharge pressure, whereby the combined action of said motors maintains the pump on leakage stroke position at a relatively low pressure. 65

4. In a fluid system, the combination with a variable stroke pump, of a fluid motor operated by 70 said pump, adjustable resilient means for placing said pump on stroke, means for controlling the operation of said fluid motor including a valve, means for returning said pump to leakage stroke position, said last mentioned means comprising a pair of servo motors, one of said servo motors 75

- being constantly connected to the discharge pressure in the system and adapted to return the pump to leakage stroke position when the pressure in the system exceeds a predetermined value, means for actuating said valve to control the operation of said fluid motor and to connect the second of said servo motors to said discharge pressure whereby the combined action of said servo motors on said pump maintains the latter on leakage stroke at a comparatively low pressure.
5. In a fluid control system, the combination with a high pressure pump and a low pressure pump, resilient means for placing said high pressure pump on stroke, automatic bypass means for rendering said low pressure pump ineffective when the pressure in the system exceeds a predetermined value, and a plurality of means for returning said high pressure pump to leakage stroke position, one of said means being adapted to maintain said high pressure pump on leakage stroke position at a comparatively high pressure, and means for conditioning another of said last mentioned means for operation, whereby said high pressure pump is maintained on leakage stroke position at a comparatively low pressure by the combined action of said pump actuating means.
6. In a fluid control system, the combination with a high pressure pump and a low pressure pump, adjustable resilient means for placing said high pressure pump on stroke, automatic bypass means for rendering said low pressure pump ineffective when the pressure in the system exceeds a predetermined value, and a plurality of fluid motors for returning said high pressure pump to leakage stroke position, one of said motors being adapted to maintain said high pressure pump in neutral position at a comparatively high pressure, and valve means for conditioning another of said fluid motors for operation whereby said high pressure pump is maintained on leakage stroke position at a comparatively low pressure by the combined action of said fluid motors.
7. In a fluid system, the combination with a fluid motor comprising a pair of cylinders, a pressing piston operative in one of said cylinders and a holding piston operative in the other of said cylinders, said pistons being adapted for relative movement, of a pump for actuating said pistons, means for placing said pump on discharge stroke, hydraulic connections between said pump and said cylinders, a pair of valves for controlling the sequence of operation of said pistons, said valve when adjusted to one position causing both of said pistons to move simultaneously in one direction, means for actuating said pump toward leakage stroke position and retaining the same in said position when said pistons reach the limit of their travel in said direction, means for adjusting one of said valves to another of its positions of adjustment causing said pressing piston to move toward said holding piston while retaining the latter against movement, and means for actuating the other of said valves to another of its positions of adjustment, whereby said holding piston will move in the same direction as said pressing piston moves in its last mentioned movement.
8. In a fluid system, the combination with a fluid motor comprising a pair of cylinders, a pressing piston operative in one of said cylinders, and a holding piston operative in the other of said cylinders, said pistons being adapted for relative movement, of a pump for actuating said pistons, means for placing said pump on discharge stroke, valve means for controlling the sequence of operation of said pistons, said valves when adjusted to one position causing said pressing piston to move toward said holding piston while retaining the latter in holding position, means for actuating said pump toward leakage stroke position and retaining the same in said position at a relatively high pressure, means for actuating said valve means to another position of adjustment causing said pressing piston to move away from said holding piston, and additional means operative in conjunction with said pump actuating means for actuating said pump toward leakage stroke position when said pressing piston reaches the limit of its travel away from said holding piston, whereby said pump is held on leakage stroke at a reduced pressure.
9. In a fluid system, the combination with a fluid motor, comprising a pair of cylinders, a pressing piston operative in one of said cylinders and a holding piston operative in the other of said cylinders, said pistons being adapted for relative movement, of means for operating said pistons including a high pressure pump and a low pressure pump, automatic means for rendering said low pressure pump ineffective when the pressure delivered to said pistons exceeds a predetermined value, adjustable resilient means for maintaining said high pressure pump on stroke, a plurality of servo motors for returning said high pressure pump to leakage stroke position under predetermined conditions, one of said servo motors being constantly connected to the discharge pressure in said system, a plurality of valves for controlling the sequence of operation of said pistons, said valves when operated to one position causing said pistons to move simultaneously in one direction by the combined discharges of said pumps, and at the same time connecting the other of said servo motors to said discharge pressure, whereby, when said pistons reach the limit of their travel in said direction the pressure developed in said system first actuates said automatic means to render said low pressure pump ineffective, and at a higher predetermined pressure said high pressure pump is rendered ineffective by the combined action of said servo motors, means for actuating one of said valves to another of its positions of adjustment, thereby causing said pressing piston to move toward said holding piston, while retaining the latter against movement, and at the same time disconnecting one of said servo motors whereby said pump is actuated toward leakage stroke position at a still higher predetermined pressure, and means for actuating another of said valves to another position of adjustment, whereby said holding piston moves in the same direction as said pressing piston.

HENRY W. LANDENBERGER.
